SIGN HOLDER FOR SHOPPING CART HANDLES OR THE LIKE

Wayne A. Drugan, Valley City, N. Dak., and Murry J. Laub, Edina, Minn., assignors to Drugan-Severson, Inc., Valley City, N. Dak., a corporation of North Dakota

Filed July 16, 1965, Ser. No. 86,182

Term of patent 14 years

(Cl. D1—12)

FIGURE 1 is a front perspective view of a sign holder for shopping cart handles or the like embodying my new design;

FIGURE 5 is a perspective view of half of the sign holder for shopping cart handles or the like, the other half being substantially the same.

The dominant features of our design reside in the portion shown in full lines, it being understood that the broken line representation of a portion of the shopping cart handle is for the purposes of illustration only.

We claim:

The ornamental design for a sign holder for shopping cart handles or the like, as shown and described.
